SHOE UPPER GUARD

Luke Prejean, Baton Rouge, La.

Application April 23, 1947, Serial No. 743,430

3 Claims. (Cl. 112—40)

1

My present invention relates generally to leather sewing machines and more specifically to an improved shoe upper guard as an attachment to shoe stitching machines of the type employing a curved needle and equipped with various forms of work tables that are utilized in stitching operations, for the manufacture as well as the repair of shoes.

In the various standard types of curved needle stitching machines used for sewing shoes, the shoe upper while being manipulated is brought close to the field of operations of the looper and take-up devices which carry a wax thread. The wax is maintained in a fluid state by heating the looper and take-up, and if and when the shoe upper contacts with these parts it is likely to be marred, soiled, or otherwise damaged; and in some instances the shoe upper may come in contact with the thread, which may result in sticking of the wax to the upper. The hot wax is difficult to remove from the upper, and therefore time and labor are lost in removing the wax and consequent expense is added to the cost of the machine operations.

The primary object of the invention is the provision of an attachment for the machines that will eliminate these objectionable and costly conditions, and at the same time guard the upper from being pierced by the awl and curved needle of the sewing machine, thereby insuring high grade quality of merchandise together with excellent workmanship. The guard or shield device of my invention is constructed and installed with relation to the curved needle in such manner as not to interfere with the threading and rethreading of the needle; and the necessary adjustments of the various operating parts of the sewing machine may be made without interference from the attachment.

To this end the invention consists in certain novel features of construction and combinations and arrangements of parts as will hereinafter be described, and more specifically set forth in the appended claims.

In the accompanying drawings I have illustrated one complete example, and several modifications, of a physical embodiment of my invention in which the parts are combined and arranged in accord with modes I have devised for the practical application of the principles of my invention. It will, however, be understood that changes and alterations are contemplated and may be made in these exemplifying drawings and mechanical structures, within the scope of my claims, without departing from the principles of my invention.

2

Figure 1 is a left side view in elevation of so much of a curved needle shoe stitching machine as is necessary to illustrate the installation, the relation of parts and the utility of the guard of my invention.

Figure 2 is a front view in elevation as seen from the right in Fig. 1 showing the guard or shield.

Figure 3 is a front elevation of the guard, detached.

Figure 4 and Figure 5 are front elevations of modified forms of the guard or shield adapted to fit standard work tables.

Figure 6 is a front view of the supporting bracket for the guard, and

Figure 7 is a detail sectional view at line 7—7 of Figure 6 showing the hinged mount for the guard.

In order that the general arrangement and relation of parts may readily be understood I have shown in Fig. 1 portions of operating parts of a standard curved needle shoe sewing machine in which the needle is designated as N, the machine frame as F, and the looper L, all of which are well known parts of the sewing machine.

In carrying out my invention I employ a guard or shield 1 of sheet metal, as steel, having a generally concavo-convex shape, with a rounded and reduced bottom edge 2 and a rounded notch 3 at its upper edge adapting the shield for use with various types of sewing machines, and roughly the shape of the shield approximates a heart shape.

In the installation of the guard as an attachment for the shoe sewing machine, the guard or shield is mounted on the worktable of the machine, and it is pivotally mounted or hinged, in order that it may be shifted as to its position to gain access to various parts of the machine when necessary.

For this purpose the guard is hinged at 4 by pin 5 to a guard portion of the supporting bracket 6 of curved and angular shape and the bracket is provided with a thin flat plate providing an attaching flange 7 positioned between the table and machine frame, as shown in Figure 1, and which is fashioned with an open end slot 8 for adjustment with relation to the pin 9 of the frame F; and in addition the attaching flange is provided with a hole 10 for the attaching screw 11, that insures a rigid fastening on the frame F.

The hinged guard on its approximately vertical axis may be swung to open position for access to the guarded operating parts, and in closed position it is latched or locked by means of a lever arm or latch 12 that is pivoted at 13 on

the rear side of the guard or shield, and this latch is adapted to engage a hasp or keeper 14 mounted on the bracket 6.

In Fig. 1 the guard is locked or latched securely in position with relation to the bracket and the operating parts.

For re-threading the machine, or for other purposes, the shield or guard may be unlocked or unlatched by lifting and swinging the latch arm to clear its hasp or keeper, and then the arm, which is fashioned of resilient material may be swung downwardly clearing the adjacent parts as it is pushed slightly toward the machine, thus permitting the shield or guard to be swung to the left in Fig. 2 to gain access to the desired parts.

After re-threading the needle, the guard is closed, and the latch bar or resilient lever arm is swung on its rivet or pivot 13, and again engaged with its hasp or keeper, and the guard is in the position for the performance of its functions.

In the form of the shield or guard in Figs. 4 and 5 the respective notches 3a and 3b are more angular in shape than the concave shape of notch 3 in Figs. 2 and 3, thus adapting the guard to other standard types of shoe sewing machines.

The open end slot 8 and the screw hole 10 in the attaching flange of the bracket 6 are made of ample size in order that the bracket may be shifted or adjusted to fit the work tables of different types of sewing machines, and the guard may be attached to machines now in use by merely boring or drilling the necessary holes for the pin 9 and screw or bolt 11.

The shield or guard is provided with a stop lug 15 forming part of the bracket 6 that prevents excessive movement of the shield, and contacts with the latch or lock lever in holding the shield in rigidly mounted position.

Having thus fully described my invention, what I claim as new and desire to secure by Letters Patent is:

1. A guard for shoe sewing machines comprising a bracket adapted to be attached to the sewing machine frame, said bracket having an attaching portion and a guard portion extending at an angle with respect to the attaching portion, a guard member hingedly attached to the bracket 45

and adapted to extend laterally from its guard portion, a locking latch pivoted on the guard member, said bracket having a keeper portion for receiving the latch whereby the guard member can be held in lateral alignment with the guard portion of the bracket.

2. A guard for shoe sewing machines comprising a bracket adapted to be attached to the sewing machine frame, said bracket having an attaching portion and a guard portion extending at an angle with respect to the attaching portion, a guard member hingedly attached to the bracket and adapted to extend laterally from its guard portion, a locking latch pivoted on the guard member, said bracket having a keeper portion for receiving the latch whereby the guard member can be held in lateral alignment with the guard portion of the bracket, and said bracket having a stop lug for limiting the rearward pivotal movement of the guard member on the bracket.

3. A guard for shoe sewing machines comprising a bracket adapted to be attached to the sewing machine frame, said bracket having an attaching portion and a guard portion extending at an angle with respect to the attaching portion, a guard member hingedly attached to the bracket and adapted to extend laterally from its guard portion, a locking latch pivoted on the guard member, said bracket having a keeper portion for receiving the latch whereby the guard member can be held in lateral alignment with the guard portion of the bracket, and said bracket having an open end slot and a screw hole spaced therefrom adapted to respectively receive a fastening pin and an attaching screw.
